AIRPLANE SAFETY DEVICE

Filed March 27, 1946

Fig. 1.

UNITED STATES PATENT OFFICE

2,591,602

AIRPLANE SAFETY DEVICE

Matt V. Pilcher, Sarasota, Fla.

Application March 27, 1946, Serial No. 657,555

8 Claims. (Cl. 137—144)

1

This invention relates to airplane safety devices, and more particularly aims to provide an improved device to prevent the pilot from taking off while the gasoline supply is cut off.

Heretofore there have been frequent accidents caused by failure of the pilot to turn on the gasoline supply valve before the take-off, resulting in power failure at the critical moment of leaving the ground. Such accidents have been possible since there usually is enough gasoline in the carburetor and supply pipes to enable the pilot to get off the ground without turning on the supply from the gasoline storage tanks, particularly if the airplane has just landed and needs no extended warm-up. The resulting power failure, of course, causes a forced landing, and the very grave possibility of serious injury.

The primary object of the present invention, therefore, is to provide a construction which will prevent movement of the throttle to take-off position so long as the gasoline supply valve remains closed.

A further object is to provide a construction in which the airplane engine may be started without turning on the gasoline supply, but in which the natural manipulation of the throttle lever by the pilot will assure its becoming locked in non-take off position if the gasoline supply is not turned on.

A further object is to provide a construction in which the throttle must be moved to a non-take off position before the gasoline supply valve can be moved to off position, and in which the throttle cannot be moved to take-off or substantially "open" position until the gasoline supply valve is moved to the open or "on" position.

Further objects and advantages of the invention, as will appear from the following description of preferred embodiments thereof, reside in the provision of improved features and arrangements of parts contributing to the realization of the aforesaid objects.

In the accompanying drawings of preferred embodiments illustrative of the invention:

Fig. 1 is a front elevation of a portion of an instrument panel of an airplane provided with interlocking throttle and fuel valve controls according to the invention.

Fig. 2 is a side elevation partly in section, on a vertical central plane through Fig. 1, showing the parts in interlocking position.

Fig. 3 is a similar view showing the parts in flight position.

Figs. 4 and 5 are front elevations of a portion of an instrument panel of an airplane provided with a modified embodiment of the invention, with

2

the parts in flight- and interlocked-position, respectively, and Fig. 6 is a side elevation of the structure of Fig. 5 partly in section with respect to the panel mounting elements.

5 The conventional two or four place airplane is ordinarily provided with one throttle rod or handle placed midway in the instrument panel so that it is available from either side. This throttle control is usually a simple shaft or rod 10 with a handle attached and reciprocable through the instrument panel. To open the throttle the handle is pushed inwardly toward the instrument panel. To close it the handle is pulled outwardly toward the pilot. For purposes of illustration 15 the present invention is shown in the drawings as applied to this conventional form of throttle control.

In the illustrative embodiment of Figs. 1 to 3, the fuel valve control handle 10 is preferably 20 associated directly with the throttle control 11 which is shown in the form of a rod provided with the usual knob or handle 12 at its outer end. In this arrangement the control handle 10 is carried by a sleeve 13 which is rotatably mounted 25 in a bushing 14 carried by the instrument panel 15. Secured to sleeve 13 behind the panel 15, in any suitable manner, as by set screw 16 is a drive pinion 17, which meshes with a driven pinion 18 secured on the stem 19 of a fuel cut-off valve 20, shown in Fig. 2 as of the rotary plug type, and interposed in the main fuel supply line 21. The cut-off valve 20, in the form shown, is suitably supported, as by securement to a structural element of the instrument panel 22, for example, by 35 bolts 23, which in the form shown, also secure in place a spline-plate 24 engaging with spline grooves 25 in the throttle control rod 11 to prevent rotation of the throttle rod for the purpose hereinafter described.

40 The structure thus far described provides a throttle control 11—12 for controlling the speed of the engine of the aircraft, a fuel line 21 for conducting fuel to said engine, a cut-off valve 20 in the fuel line, and means, in the form of handle 45 10 which is coupled through sleeve 13 and gear train 17—18 for moving the cut-off valve to open and closed positions to control the flow of gasoline from the fuel tanks through pipe 21 to the carburetor of the engine. As shown in Fig. 1, 50 suitable legends may be provided for the guidance of the pilot in manipulating the controls, such legends being engraved on the instrument panel or control knobs, as desired.

In accordance with the invention the structure above described is further provided with an

3

interlock controlled by the movement of the valve moving means 10 and arranged to prevent movement of the throttle control 11-12 from its closed throttle position (Fig. 2) to its open throttle or take-off position (Fig. 3) when the cut-off valve 20 is in its closed position.

As shown in Figs. 2 and 3, this interlock may take the form of a latch comprising the spring-pressed bolt or detent member 30, herein housed, with its spring 31, in a transverse bore 32 within the handle 10. Since the rod 11 passes through sleeve 13, and bore 32 is transverse of this sleeve, assembly is facilitated as the spring and bolt, inserted in bore 32, are held in place therein by insertion of the rod 11. The latch, of course, further comprises a keeper, herein formed as an abutment 33 provided by a notch or recess 34 formed in the side of the throttle control rod 11 in position to be engaged by bolt 30 when the throttle control 11, 12 and fuel valve 20 are both in closed position (Fig. 2). In this form of the invention, in which the throttle control rod 11 passes through the bore of the sleeve 13 through which the cut-off valve 20 is operated, rotation of sleeve 13, as will be apparent from Fig. 3, moves bolt 30 to an inoperative position, misaligned with recess 34, as soon as the fuel valve handle 10 is moved to practically full open position. To assure this action means is provided to prevent rotation of the throttle control rod 11, this means, as above described, comprising the spline plate 24 engaging with spline grooves 25, or the like. As shown in Figs. 2 and 3, in this arrangement it is preferable to arch somewhat the bottom of the recess 34, as this insures smoother working of the parts. The abutment 33, as shown, may be positioned to allow sufficient opening of the throttle for starting and slow running of the engine without opening of the fuel valve 20.

With the arrangement of Figs. 1 to 3, it will be appreciated that the fuel supply may be cut off by manipulation of the handle 10 while the throttle is in open position. Thus, on landing, the fuel valve 20 may be closed and the engine may be operated at full taxiing speed on the residual gasoline in the carburetor and lines until the latter is exhausted, thus effecting quick draining of the lines and carburetor to facilitate servicing thereof, and to reduce fire hazard. If this is not done on landing, so that the carburetor and lines retain their fuel content, the engine may be started without moving the throttle control to full closed position. However, on starting of the engine under these circumstances, the natural reaction of the pilot is to pull out the throttle to slow-speed or idling position, whereupon latching of bolt 30 behind the abutment 33 occurs, preventing movement of the throttle to take-off position until the fuel valve control 10, 13, is moved to open the valve 20.

When it is not desired to provide for quick draining of the carburetor and lines as above described, forms of the invention not providing for this feature may be employed. One such form is shown in Figs. 4 to 6. In this instance, the fuel valve control 40 is in the form of a slide member and is associated with the throttle control 41 having the usual knob or handle 42 at its outer end. In this arrangement the slide 40 is suitably supported, as by studs or the like 43, which are slidably mounted in slots 44 formed in the instrument panel 45. Suitable means is provided for associating the slide 40 with the fuel

4

cut-off valve to be operated thereby, herein illustrated as a driving rack 47 secured on certain of studs 43, as by nuts 46 (see Fig. 6) and meshing with a driven pinion 48 secured on the stem 49 of the fuel cut-off valve which may be suitably supported in any desired manner, that indicated in connection with valve 20 and supporting means 22-23 in Fig. 2 being suitable, for example. As above mentioned, suitable legends may be applied for the guidance of the pilot in manipulating the controls (see Figs. 4 and 5).

The interlock in this arrangement is effected by providing the slide-member 40 with a projecting bolt, and preferably two such bolts in the form of a bifurcated end 50, adapted to be moved by movement of the slide 40 (which may be provided with the finger-hold 51 to facilitate its movement) into engagement behind shoulder- or keeper-abutment means 53 (Figs. 4 and 6) provided by recesses 54 milled or otherwise formed in the sides of throttle control rod 41.

In this form of the invention, it will be apparent, slide 40 can be moved to turn the valve stem 49 to closed position only when the throttle control 41-42 is moved to closed position. This arrangement thus makes it impossible to turn off the fuel supply by moving the normal cut-off slide 40 while the throttle is in flight position. Similarly, throttle control 41-42 is locked in closed, or nearly closed position, whenever the fuel valve is in closed position. This arrangement thus provides a two-way interlock and insures against cutting off the fuel supply while the airplane is in operation, as well as insuring against take-off of the airplane without opening of the fuel valve. In addition, by arranging the parts so that the ends of fork 50 are withdrawn from the notches 54 only when the slide 40 is moved to substantially full-open position, as shown, insurance is afforded against faulty operation due to restriction of the fuel supply by failure to fully open the cut-off valve.

From the foregoing it will be apparent that the embodiments shown and described are but illustrative and not restrictive of the invention herein described and claimed, and that inventive features and combination of this disclosure may be embodied in other specific forms.

I claim:

1. A safety device for an airplane of the type having a longitudinally reciprocable throttle rod for controlling the speed of the engine of the airplane and longitudinally movable from a closed or engine idling position to a substantially open position permitting take-off of the airplane, a fuel line for supplying fuel to the engine of the airplane, a valve in said fuel line, and means for moving said valve to open and closed positions; said safety device comprising an interlock controlled by the movement of said valve-moving means, which, in the closed position of said valve, intercepts said longitudinally reciprocable throttle rod in its closed or engine idling position and prevents its longitudinal movement to said substantially open take-off position, and which, when said valve has been opened and said throttle has been moved to its substantially open position, is incapable of preventing longitudinal movement of said throttle to its closed or engine idling position.

2. An airplane safety device according to claim 1, said interlock comprising a latch having a bolt and a keeper adapted to interengage to lock said throttle in its closed throttle position, said bolt

In the open position of said fuel valve being moved to an inoperative position with respect to said keeper.

3. An airplane safety device according to claim 1, said interlock comprising a latch having a spring pressed bolt and a keeper adapted to interengage to lock said throttle in its closed throttle position, said bolt in the open position of said fuel valve being moved to an inoperative position misaligned with respect to said keeper.

4. An airplane safety device according to claim 1, said interlock comprising a bolt member movable by said valve moving means, a keeper abutment movable with said throttle, said keeper abutment preventing closing of said valve when said throttle is in said substantially open take-off position, and said slide member preventing movement of said throttle to said substantially open take-off position when said valve is closed.

5. A safety interlock for preventing opening of the throttle of an airplane engine when the fuel cut-off valve between the fuel tanks and the carburetor of the engine is closed; said interlock comprising a reciprocating throttle rod for opening and closing the throttle of the engine, a member for actuating the fuel cut-off valve between the fuel tanks and the carburetor of the engine, said cut-off valve actuating member being juxtaposed to said reciprocating throttle rod, a bolt carried by said valve actuating member and moved to locking position by the movement of said valve actuating member to valve closing position, a notch formed in said throttle rod and located to align with said bolt when said throttle rod is in throttle closing position, said bolt entering said notch when both said valve actuating member and said throttle rod are in their respective valve-closing and throttle closing positions.

6. A safety interlock for preventing opening of the throttle of an airplane engine when the fuel cut-off valve between the fuel tanks and the carburetor of the engine is closed; said interlock comprising a bushing, valve actuating means comprising an actuating sleeve journalled in said bushing and rotatable therein for opening and closing the fuel cut-off valve between the fuel tanks and the carburetor of the engine and means for rotating said sleeve to valve opening and valve closing positions, a reciprocating throttle rod slidable in said sleeve for opening and closing the throttle of the engine, a spring-pressed bolt housed within said valve actuating means and bearing against said throttle rod, said throttle rod having a notch entered by said bolt when both said valve actuating means and said throttle rod are in their respective valve-closing and throttle closing positions.

7. A safety interlock for preventing opening of the throttle of an airplane engine when the fuel cut-off valve between the fuel tanks and the carburetor of the engine is closed; said interlock comprising a bushing, valve actuating means comprising an actuating sleeve journalled in said bushing and rotatable therein for opening and closing the fuel cut-off valve between the fuel tanks and the carburetor of the engine and means for rotating said sleeve to valve opening and valve closing positions, a reciprocating throttle rod slidable in said sleeve for opening and closing the throttle of the engine, means locking said rod against rotation, a spring-pressed bolt housed within said valve actuating means and bearing against said throttle rod, said throttle rod having a notch formed in its side and having an arched bottom, said notch being entered by said bolt when both said valve actuating means and said throttle rod are in their respective valve-closing and throttle closing positions and being disengaged from said bolt on turning of said valve actuating means about said rod.

8. A safety interlock for preventing opening of the throttle of an airplane engine when the fuel cut-off valve between the fuel tanks and the carburetor of the engine is closed; said interlock comprising a panel element, a throttle rod reciprocable therethrough for opening and closing the throttle of the engine, said rod having a keeper abutment lying forwardly of the panel element in the throttle-closing position of the rod, a bolt member lying forwardly of the panel element, said bolt member positioned to be movable to engage and disengage said abutment, a valve actuating member for opening and closing the fuel cut-off valve between the fuel tanks and the carburetor of the engine, and a connection by which said valve actuating member moves said bolt to engage said abutment when said valve actuating member is moved to close the fuel cut-off valve.
